UNITED STATES PATENT OFFICE.

EBENEZER BUTTERICK, OF BROOKLYN, NEW YORK.

EGG-CASE.

SPECIFICATION forming part of Letters Patent No. 417,469, dated December 17, 1889.

Application filed June 27, 1888. Serial No. 278,335. (No model.)

To all whom it may concern:

Be it known that I, EBENEZER BUTTERICK, of Brooklyn, in the county of Kings and State of New York, have invented a new and Improved Egg-Case, of which the following is a full, clear, and exact description.

My improvement relates to the class of egg-carriers in which a series of horizontal pockets are detachably secured within a transporting-frame, each pocket consisting of a series of complete cells arranged end to end, which may be filled before placing the pocket within the frame; and my invention has for its object to provide a carrier in which the egg can be safely transported without danger of breaking or decay, and one which can be quickly packed or unpacked when desired.

Reference is to be had to the accompanying drawings, in which—

Figure 1 is a top plan view of an egg-case constructed in accordance with my invention, the frame being open and the upper portion of one set of cells being removed. Fig. 2 is a longitudinal section on line 2 2 of Fig. 1, the frame being closed. Fig. 3 is a transverse section of one of the cells shown in Figs. 1 and 2. Fig. 4 is a view on an enlarged scale, showing the connection of the dividing-disks *c c* with the pockets. Fig. 5 is a perspective view of one set of cells, showing the pockets opened and detached from the frame. Fig. 6 is a view showing the case when constructed of metal. Figs. 7 and 8 are views illustrating the same when constructed of wire, and Fig. 9 is a cross-section of one of the pockets shown in Fig. 6.

In carrying out my invention I employ the horizontal pockets *B*, made in two parts *b b'*, hinged together at *h*, and said pockets consist of a series of egg-shaped cells or receptacles arranged end to end and completely separated from each other by the disks *c*, the ends of the series having pintles or journals *d d* formed on their outer disks, by means of which the pockets may be journaled or secured within a transporting-frame *A*. This frame *A* is made in two sections, hinged as shown, and is deeper than the egg-pockets *B*, so that, if desired, a number of such frames packed with eggs may be placed one upon another without endangering the eggs. The

pockets may be of pasteboard or other pressed plastic material, sheet metal, or any other suitable material, and the pocket parts can be made in one piece or a number of pieces, 55 as desired, and wire may be used to form the pockets, as shown in Figs. 5 and 6.

In making the pocket parts *b b'* of pasteboard, the pasteboard of the desired length is narrowed at intervals and pressed to form 60 the series of half-cells *e e*, and between the half-cells are formed the neck or intermediate portion *C C*. The disks *c c*, which complete the half-cells, are fastened by glue or other material to one pocket part *b* at the 65 ends of each half-cell, and register with the neck or intermediate portion *C* of the other pocket part *b'*. If desired, however, these disks may be divided transversely on the line of division of the pocket part and the 70 half-disks secured in the same manner as the disks *C*. The upper and lower pocket parts *b b'* are then hinged together, as at *h*, and are provided with a hook and catch *l m*, by which the two parts are securely held together while 75 handling. The pintles or journals *d d* are secured to the outer end disks of one of the pocket parts by gluing or otherwise, and rest in bearings in the frame when the pockets are to be transported. The pockets may or may not be 80 provided with perforations or slits for ventilation, as is thought best, and the pocket parts, including the disks, may, if desired, be formed of plastic material pressed in a mold.

In constructing the pockets of sheet metal 85 the same method of construction may be followed as in the pasteboard pockets, or they may be made of a series of strips extending the entire length of the pocket, pressed to the proper shape and securely held in position by the metallic bands *s s'*, soldered upon the outer side of the strips at their converging part, or, if necessary, they may be made of a series of strips, each as long as the cell *e* and soldered together at the band *s'*. The 90 outer end disks *c c* carry upon their outer sides the pintles or journals *d d*, which are soldered or otherwise secured to said disks, and the pocket parts *b* and *b'* are hinged and locked in a manner similar to the pasteboard 95 pockets.

When it is desired to form the pocket parts

of wire, as shown in Figs. 7 and 8, a number of wires of the desired length are pressed into proper shape and securely held by soldering them to the metallic hoops or band S'', 5 arranged at the end of each cell. These bands S'' S'' have each a hook h at one end, by means of which the two pocket parts are hinged together. The securing-bands S'' S'' 10 pass around the outside of the pocket and soldered on the inside, at the end of the cells, and between them are the metallic half-disks c.

In the wire pockets the disks may be whole or divided, and the attachment of the pintles 15 and catch is similar to those of pasteboard and sheet-metal pockets.

To facilitate the packing and unpacking the pocket may be formed with one part deeper than the other, and having the deeper 20 side under when packing the eggs can be packed quicker and with less danger, and by having the shallow part under when unpacking the eggs can be removed much easier.

In operation the pocket parts are first filled 25 with eggs, securely fastened, and then placed in one section of the frame A. The other frame section is then turned down and fastened, thus securely holding the pockets in place during transportation.

Having thus described my invention, what 30 I claim, and desire to secure by Letters Patent, is—

1. In an egg-carrier, a pocket consisting of a number of elongated cells connected to

35 together, end to end, the end cells being provided with pintles for supporting the pocket in a case, substantially as described.

2. In an egg-carrier, the pocket B, made in two parts b b', hinged together at h, said 40 pockets consisting of a series of egg-shaped cells arranged end to end and separated from each other by the disks c, secured at the ends of each cell, the outer end disks of each pocket being provided with a journal or pin- 45 tle d, by means of which the pocket is journaled within the transporting-frame A, substantially as shown and described.

3. A pocket for holding eggs, made in two hinged parts, consisting of a series of strips bent to conform to the shape of the eggs, the 50 bands s, secured to the outer side of the strips at their converging parts and holding the same securely in position, the concave disks c, secured within the cells at each end of the same, and the pintles d, attached to the outer 55 end disks of each pocket, substantially as shown and described.

4. In an egg-carrier, the pocket B, consisting of a series of egg-shaped cells arranged end to end, the said pocket being formed of 60 two parts b b', hinged together and provided at its ends with pintles d, for supporting it in a frame, substantially as herein shown and described.

EBENEZER BUTTERICK.
